(57) **CLAIM**

The ornamental design for the eyeglass display, as shown and described.

DESCRIPTION

FIG. 1 is an isometric view of an eyeglass display showing my design;

FIG. 2 is a front view of the eyeglass display of FIG. 1;
FIG. 3 is a rear view of the eyeglass display of FIG. 1;
FIG. 4 is a right side view of the eyeglass display of FIG. 1;
FIG. 5 is a left side view of the eyeglass display of FIG. 1;
FIG. 6 is a top view of eyeglass display of FIG. 1; and,
FIG. 7 is a bottom view of the eyeglass display of FIG. 1.
The dashed lines shown in the figures represent environmental subject matter and form no part of the claimed design.
